UNITED STATES PATENT OFFICE.

HERMANN V. FENGLER, OF WEST PHILADELPHIA, PENNSYLVANIA, ASSIGNOR TO
UNDERWOOD TYPEWRITER COMPANY, OF NEW YORK, N. Y., A CORPORATION OF
DELAWARE.

TYPE-WRITING MACHINE.

1,232,521.

Specification of Letters Patent. Patented July 10, 1917.

Application filed May 11, 1915. Serial No. 27,303.

To all whom it may concern:

Be it known that I, HERMANN V. FENGLER, a citizen of the United States, residing in West Philadelphia, in the county of Philadelphia and State of Pennsylvania, have invented certain new and useful Improvements in Type-Writing Machines, of which the following is a specification.

This invention relates to mechanism for 10 rotating the platen of a typewriting machine through predetermined fixed distances, which may be greater than an ordinary line-space distance, to facilitate the feeding of sheets, envelopes, or other work-pieces rapidly around the platen, and which may serve, by a single operation, to advance a work-piece from its introductory position to bring a predetermined point on the work to the printing line on the platen. The platen-rotating means may also be used for ejecting 20 the work-piece from the machine, or, in general, for any work where a rotation of the platen through a considerable distance at a single operation may be utilized.

25 The invention may comprise a platen driver, adapted to be reciprocated between fixed stop positions, and operable when moved in one direction to rotate the platen, but returnable independently thereof, so that 30 the platen is only rotated thereby in one direction. Adjusting means may be provided to vary the extent of rotation imparted to the platen by a complete operation of the driving means. The driving means may 35 thus be adapted for use as a line-spacer for rotating the platen through usual line-space distances, or greater line-space distances than permitted by the ordinary line-spacing mechanism, or through still greater distances as may be required, for example, to place in position on the platen, for the first line of writing, a bill, envelop, or other work-piece.

40 A feature of this invention is the provision of means whereby the platen-rotating mechanism cannot be coupled to the platen at any other than the normal starting position of the said mechanism, thus insuring the accurate rotation of the platen.

45 Another feature relates to the means for positively locking the platen-rotating mechanism to the platen until the operator releases the operating handle.

Another feature is the provision of a sin-

gle means for stopping the platen after having been rotated through the predetermined distance, for disconnecting the mechanism from the platen after pressure has been relieved from the operating handle, and for returning the parts to normal positions after the handle has been released.

Another feature is the provision of means whereby the stopping point of the mechanism may be varied at will, and also the provision of a scale for indicating the extent 65 the platen is rotated at each complete operation of the platen-rotating mechanism.

In carrying out this invention, an operating lever may cause a pawl to engage and drive a gear fast to the platen axle, the 70 first part of the movement of the lever causing the pawl to engage said gear, and to be locked thereto, while the continued movement of the lever may cause the pawl to drive the gear and rotate the platen. The 75 pawl and lever may be returned by a coiled spring, which may have one end fast to the platen-driving means, while the other end may be fixed. The spring may be wound by the forward rotation of the driver and serve 80 as a stop to limit said rotation.

A disk which may hold the fixed end of the spring, may be mounted concentrically with the platen axle, so as to be adjustable rotatively, and thereby partly unwind or 85 wind the coiled spring, which will vary the amount of rotation that can be given to the driving member and platen before the spring will be wound to its full capacity, arresting the pawl and operating lever. The disk may 90 be held in its adjusted position by means of a stationary rack with which engages a tooth or teeth on the disk, the disk being spring held in engagement with the rack. This disk may be provided on its periphery with 95 a scale to coöperate with an index on the machine, to indicate the extent of rotation which may be given to the platen by a single operation of the driver.

The coiled spring may also be used to return the parts to normal positions after the operating lever is released, and in so doing it may uncouple the driving pawl, so that the pawl and gear cannot again be coupled until the parts are fully returned to normal 105 position.

Other features and advantages will hereinafter appear.

In the accompanying drawings,

Figure 1 is a fragmentary perspective view of the carriage and platen frame of an Underwood typewriter, showing my improved gross line-spacing mechanism after having rotated the platen through ten line-spaces.

Fig. 2 is a fragmentary front sectional elevation of my improved line-spacing mechanism.

Fig. 3 is a disassembled view showing the casing of the mechanism, the driving pawl and disk by which it is carried, the gear on the platen axle, and the driving disk showing the driving band and the coiled leaf spring attached thereto.

Fig. 4 shows the adjustable disk and the spring which co-operates therewith.

Fig. 5 is a side elevation showing the parts in normal position with parts broken away, to show the relation between the pawl and the gear wheel when the parts are in this position.

Fig. 6 is a sectional side elevation showing the handle moved just enough to cause the pawl to engage the gear wheel.

Fig. 7 is a fragmentary side elevation, showing the parts after having moved several line-spaces. This view shows the pawl carrying disk being positively driven by the driving disk, and also shows the spring so tensioned, that the rotation of the parts is very limited.

Fig. 8 is a fragmentary side elevation, showing the parts at the end of a forward stroke, the pressure of the operator's hand still being applied to the lever.

Fig. 9 is a fragmentary side elevation showing the parts after the pressure has been released, the parts being in the act of returning to normal position.

Fig. 10 is a diagrammatic view showing the relative position of the pawl and lever, and the work-sheet just before the operation of the lever to insert the work-sheet.

Fig. 11 is a diagrammatic view showing the relative position of the pawl, the lever, and the paper in the act of being rotated at the operation of the lever.

The usual platen 1 of an Underwood typewriter is secured to an axle 2, rotatably mounted in the end plates 3 of the platen frame, the ends of the axle 2, projecting past the end plates 3 of the platen frame, and having finger wheels 4 fast thereon, by which the platen may be rotated forwardly or backwardly to an unlimited extent. The platen may also be rotated forwardly by the usual line-space mechanism, comprising a line-space lever 5 to operate on slide 6, having a pawl 6^a, which engages a ratchet wheel 7, fast on the platen axle.

The work-sheet, after being placed upon a paper shelf 8, is fed around into position to receive type impressions, by feed rolls 9,

10. The platen is usually rotated by the finger wheel 4, or by repeated operations of the usual line-spacing mechanism.

I provide a lever 11 which may have a hub portion 12, loosely mounted on the platen axle 2, which extends through the right hand end plate 3, and may be provided at its upper end with a handle 13, this lever having connections with the platen, whereby the platen will be rotated through the desired extent, to bring the printing point of the work-sheet to the printing line of the machine at each complete operation of said lever.

The driving connections between the lever 11 and the platen, may include a disk 14 to which the lever is connected by means of a flexible band 15, the latter being wound around the periphery of a flange 16 on said disk 14, with its end fast thereto, and extending upwardly and backwardly over a pulley 17, mounted on a stud fixed in a bracket 18, the latter fixed on the end plate 3 of the platen frame, and then forwardly to a pin 19 on the lever 11, to which it is connected.

In pulling the lever 11 forward, the band 15 is drawn over the pulley 17, and unwinds from the periphery of the flange 16 of the disk 14, rotating said disk in clockwise direction. The first part of the clockwise rotation of the disk 14, causes a cam projection 20 on the under surface of the flange 16, to force a pawl 21 into engagement with a gear wheel 22 fast on the platen axle 2.

The pawl 21 is floated above an opening 23 in a flange 24, on a disk 25, through which it extends to engage the gear 22 fast on the axle 2. The pawl is held out of engagement with said gear by a leaf spring 26, having one end fast to the pawl, while the other end is fastened to the periphery of the flange 24. The disk 25 is loosely mounted on the platen axle, and has a flange 24 extending about the periphery of the gear 22, said flange 24 being inclosed by the flange 16 of the disk 14, and being so situated with respect to disk 14 that at the independent rotation of the disk 25, the cam projection 20, carried on the inner surface of the flange 16, on the disk 14, will force the pawl 21 against the tension of the leaf spring 26 into engagement with the gear 22 on platen axle 2.

After having caused the pawl 21 to be moved into engagement with the gear 22, the disk 14 positively rotates the pawl-carrying disk 25, as shown in Fig. 7, by means of arms 27 on the disk 25, being engaged by the ends of slots 28, on the flange 16. The disk 25 is held against frictional rotation during the coupling operation, by means of a spring detent 29, fast to the casing of the mechanism, and having a dwell or portion adapted to arrest a projection 30 on the disk 25, and hold said disk until positively picked up by 130

the ends of slots 28 on the flange 16; said slots 28 being long enough to permit sufficient relative movement between the disk 14 and the disk 25, to cause the cam 20 to force 5 the pawl 21 into engagement with the gear 22.

The continued forward movement of the operating lever 11 is limited by a coiled spring 31, which when fully wound, arrests 10 all the parts, thus stopping the platen. The spring is fastened at one end to the hub of the disk 14, and has at its other end a loop 32, adapted to be slid over a pin 33, on a stationary disk 34, loosely mounted on the 15 platen axle 2.

This disk may be angularly adjusted to vary the amount of rotation that can be given to the loose end of the spring before the spring is fully wound. The disk 34 20 is held in its adjusted position by a compression spring 35, which normally holds the disk 34 against the casing, so that projections 36 on said disk 34, enter notches 37 on the casing of the mechanism. To adjust 25 the spring 31, the operator moves the disk 34 so as to free the projections 36 from the notches 37, and turns the disk around the axle 2, to wind or unwind the spring, thereby varying the amount of rotation that may 30 be given to the parts before stopped by the fully wound spring.

When the lever 11 is released at the end of a forward stroke, the parts are returned to normal positions by the spring 31. In re- 35 turning to normal position, the first action that takes place is the uncoupling of the pawl 21 and the gear 22, this occurring because the pawl-carrying disk 25, is held against frictional rotation by the pawl 21, 40 which is in engagement with the gear 22, until the disk 14 has rotated under the influence of the spring 31 sufficiently to move the cam 20 thereon, away from the pawl 21, thereby permitting the spring 26, carrying 45 said pawl, to move the pawl 21 out of engagement with the teeth of the gear 22. After this uncoupling takes place, the arms 27 of the pawl-carrying disk 24 are picked up by the opposite ends of the slots 28 in the 50 disk 14, and these return to normal position with said disk 14.

The adjustable disk 34 may be provided around its periphery with a row of numbers or a scale 38, which, when brought into register with an index 39 on the casing of the mechanism, will indicate the number of line-spaces that the platen will move at each complete operation of the lever 11. The index numbers of the scale 38 are at equal intervals with the adjusting notches 37 in the stationary drum or casing, and these notches are so spaced that each step in the adjustment of the disk 34 represents a line-space interval. That is, an adjustment of the disk 60 65 34 to move a holding lug 36 from one notch

to the next adjacent notch, effects a difference in the extent of rotation of the platen permitted by the driver, equal to a line-space interval, such interval being determined by the angular distance between 70 adjacent teeth of the line-space wheel 7.

The index pointer 39 is preferably so positioned that the index number opposite the pointer indicates the number of line-spaces through which the platen may be rotated 75 by a throw of the driving lever 11. Thus, for example, as shown in Fig. 1, the index number 10 is opposite the pointer 39, and indicates that the throw of the lever 11 will effect a rotation of the platen through ten 80 line-spaces.

The driving lever 11, together with the disk 14 and connecting band 15, forms a driver for rotating the platen, said driver being releasably connected to the platen 85 through an interponent comprising the disk 25. Said interponent disk has a lost motion connection through the lugs 27 and notches 28 with the driver, permitting the interponent to be clutched to, or unclutched from 90 the platen by means of the cam 20 controlling dog or pawl 21, said clutching and unclutching taking place during the lost motion or rotation of the driver relative to the interponent disk. 95

It will be seen that when the pawl 21 is uncoupled from the gear 22, which uncoupling takes place as the lever 11 commences its return movement, the pawl cannot again be coupled to the gear before the pawl-carrying disk 25 has been returned to its starting position, in which it is held by the detent 29. That is, a forward rotation of the driver would cause the cam 20 to drive the interponent forward without forcing the 105 pawl into engagement with its ratchet, except when the interponent is held by the detent 29. The liability of the platen receiving an incomplete rotation on account of the driving lever being thrown forward before 110 it is first completely returned to its starting position, is thereby avoided. It will be noted that the driver is at all times disconnected from the platen except when a forward pull is being applied to the driver by 115 the operator, and the driver is operative to rotate the platen forward from any position through a fixed distance indicated by the index 39. The release of the driver by the operator while the driver is in any position effects an automatic return of the driver to starting position and release of the platen. 120

Variations may be resorted to within the scope of the invention, and portions of the improvements may be used without others. 125

Having thus described my invention, I claim:

1. The combination with a platen and a driver to rotate the platen, said driver having a forward and return movement from 130

- its normal position of rest, of an interponent between the driver and platen, the interponent being disconnected from the platen while the driver is in its normal position of rest to permit the platen to be rotated independently of the driver, said driver having a lost motion connection with the interponent, the lost motion being taken up during the initial forward movement of the driver, and means operated during said initial movement to connect the interponent with the platen to rotate the latter during the continued forward movement of the driver, the interponent being released from the platen during the initial portion of the return movement of the driver, thereby permitting the platen to remain at rest during the return of the driver to its starting position.
2. The combination with a platen and a driver to rotate the platen, said driver having a forward and return movement from its normal position of rest, of an interponent between the driver and platen, the interponent being disconnected from the platen while the driver is in its normal position of rest to permit the platen to be rotated independently of the driver, said driver having a lost motion connection with the interponent, the lost motion being taken up during the initial forward movement of the driver, means operated during said initial movement to connect the interponent with the platen to rotate the latter during the continued forward movement of the driver, the interponent being released from the platen during the initial portion of the return movement of the driver, thereby permitting the platen to remain at rest during the return of the driver to its starting position, said interponent being returned to starting position when the driver is returned, and means to yieldingly hold the interponent in its starting position during said initial movement of the driver for connecting the interponent with the platen, said interponent free to be rotated by the driver without its connection with the platen being effected, when the driver is moved forward from an intermediate position without first having returned the interponent to said holding position.
3. The combination with a platen and a driver to rotate the platen, said driver having a forward and return movement from its normal position of rest, of an interponent between the driver and platen, the interponent being disconnected from the platen while the driver is in its normal position of rest to permit the platen to be rotated independently of the driver, said driver having a lost motion connection with the interponent, the lost motion being taken up during the initial forward movement of the driver, means operated during said initial

movement to connect the interponent with the platen to rotate the latter during the continued forward movement of the driver, the interponent being released from the platen during the initial portion of the return movement of the driver, thereby permitting the platen to remain at rest during the return of the driver to its starting position, means to automatically return the driver and interponent when the driver is released at the completion of its forward movement, and a stop to limit the return movement of the driver.

4. The combination with a platen, of driving means to rotate the platen, said means comprising a lever and a coupling device both rotatable about the platen axis, means connecting said coupling device and lever to cause the rotation of the lever in one direction to rotate said coupling device about the platen axis in the reverse direction, and means to connect said coupling device with the platen for rotating the platen with the coupling device in one direction and permitting the coupling device to rotate in the reverse direction independently of the platen.

5. The combination with a rotary platen and platen axle, of driving means comprising a driving lever and a coupling device both loosely mounted for rotation on the platen axle, a flexible driving connection between said lever and coupling device, directing means for said connection, whereby, when said lever is rotated in one direction, the coupling device is caused to rotate in the reverse direction, and means to connect said coupling device to the platen to rotate the latter with the coupling device in one direction and permitting the coupling device to be rotated in the reverse direction independently of the platen.

6. The combination with a rotary platen and platen axle, of driving means comprising a driving lever and a coupling device both loosely mounted for rotation on the platen axle, a flexible driving connection between said lever and coupling device, directing means for said connection, whereby when said lever is rotated in one direction, the coupling device is caused to rotate in the reverse direction, means to connect said coupling device to the platen to rotate the latter in one direction and permitting the coupling device to be rotated in the reverse direction independently of the platen, the connecting means between the coupling device and the platen comprising an interponent having a lost motion connection with said coupling device, permitting a limited movement of the coupling device relatively to the interponent, and means operated during said relative movement to connect the interponent to the platen to rotate therewith, said coupling device when rotated in the reverse direction, permitting the interponent to be

released from the platen, whereby the latter may be rotated in either direction independently of the driving means.

7. The combination with a platen and a driver to rotate the platen, said driver having a forward and return movement from its normal position of rest, of an interponent between the driver and platen, the interponent being disconnected from the platen while the driver is in its normal position of rest to permit the platen to be rotated independently of the driver, said driver having a lost motion connection with the interponent, the lost motion being taken up during the initial forward movement of the driver, means operated during said initial movement to connect the interponent with the platen to rotate the latter during the continued forward movement of the driver, the interponent being released from the platen during the initial portion of the return movement of the driver, thereby permitting the platen to remain at rest during the return of the driver to its starting position, and a spring to automatically return the driver to starting position, said spring also forming a means to limit the forward throw of the driver, and thereby determine the distance through which the platen may be rotated by an operation of the driver.

8. The combination with a platen and a driver to rotate the platen, said driver having a forward and return movement from its normal position of rest, of an interponent between the driver and platen, the interponent being disconnected from the platen while the driver is in its normal position of rest to permit the platen to be rotated independently of the driver, said driver having a lost motion connection with the interponent, the lost motion being taken up during the initial forward movement of the driver, means operated during said initial movement to connect the interponent with the platen to rotate the latter during the continued forward movement of the driver, the interponent being released from the platen during the initial portion of the return movement of the driver, thereby permitting the platen to remain at rest during the return of the driver to its starting position, and a coil spring to automatically return the driver when the latter is released at the completion of the forward throw, said spring being connected to the driver and to an adjusting device, and limiting the movement of the driver relatively to the adjusting device to thereby determine the throw of the driver, said adjusting device adjustable to vary the throw of the driver.

9. The combination with a platen and a rotary driving means for rotating the platen, of a coil spring connected at one end to the driving means, a stationary device to which 65 the other end of the spring is anchored,

said spring arranged to control the extent of rotation of the driving means in one direction by serving as a stop to limit said rotation, and a stop to limit the rotation of said driving means in the reverse direction.

10. The combination with a platen and a rotary driving means for rotating the platen, of a coil spring connected at one end to the driving means, a stationary device 75 to which the other end of the spring is anchored, said spring permitting a limited rotation of the driving means in one direction and serving as a stop to limit said rotation, and a stop to limit the rotation of 80 said driving means in the reverse direction, said device to which the spring is connected being adjustable to limit the position of the driving means determined by said spring and thereby vary the extent of rotation of 85 the driving means.

11. The combination with a rotary platen and a driver, of an interponent between the platen and driver, and having a connection with the driver permitting a limited movement of the driver relatively to the interponent, means controlled by the driver to connect the interponent with the platen during said limited movement, so that the platen is rotated by the driver during the continued 95 movement of the driver, and a spring detent to hold the interponent while the connection between the interponent and platen is being effected, said detent positioned to hold the interponent only when the latter 100 is in starting position.

12. The combination with a rotary platen and platen axle, of means for rotating the platen a predetermined fixed distance in one direction, said means comprising a driving element loosely mounted for rotation about the platen axis, an interponent having a lost motion connection with said driving element and positively driven by said element, except while said lost motion is 105 being taken up, a driving gear connected to the platen to rotate therewith, a dog carried by said interponent, means controlled by said driving element during its initial movement from starting position and while 110 the lost motion between the said element and interponent is being taken up, to move said dog into driving engagement with said gear, whereby the continued rotation of the driving element drives said interponent and 115 through said dog and gear drives the platen, and means to limit the rotation of the platen by said driver, said driving element during the initial portion of its return movement, being movable relatively to the interponent 120 to release said dog and thereby release the platen from the interponent, the latter, during the continued rotation of the driving element, being returned thereby to starting 125 position.

13. The combination with a rotary platen, of a ratchet connected thereto, a pawl movable into and out of driving engagement with the ratchet, a carrier for said pawl, a driver, said carrier forming an interponent between the driver and platen and having a lost motion connection with the driver, and a cam on the driver to move the pawl into engagement with the ratchet during the movement of the driver relatively to said carrier, said driver operable during its continued movement to positively drive said carrier and thereby drive the platen, said lost motion connection permitting the cam to be moved out of position to hold the pawl when the driver is moved in the reverse direction, whereby the pawl is released from the ratchet and the platen permitted to remain at rest during the return of the driver.
14. The combination with a rotary platen, of a ratchet connected thereto, a pawl movable into and out of driving engagement with the ratchet, a carrier for said pawl, a driver, said carrier forming an interponent between the driver and platen and having a lost motion connection with the driver, a cam on the driver to move the pawl into engagement with the ratchet during the movement of the driver relatively to said carrier, said driver operable during its continued movement to positively drive said carrier and thereby drive the platen, said lost motion connection permitting the cam to be moved out of position to hold the pawl when the driver is moved in the reverse direction, whereby the pawl is released from the ratchet and the platen permitted to remain at rest during the return of the driver, a stop to limit the return movement of the driver and pawl carrier, and means to hold the pawl carrier against movement while the driver operates to connect the pawl and ratchet, said holding means operative only when the carrier is in its starting position, whereby the driver, when released from the platen by the release of the pawl from its ratchet, can only be connected to drive the platen, by first returning the driver to starting position.
15. The combination with a platen and a reciprocating driver having a limited movement in both directions, of means whereby the driver during its movement in one direction is connected to rotate the platen through a predetermined distance, and during its return movement is prevented from rotating the platen, means to indicate said distance, said indicating means comprising a scale and pointer, means to effect a relative adjustment of the scale and pointer, and means operated by said adjustment to correspondingly vary the throw of the driver.
16. The combination with a platen, of a driver to rotate the platen, said driver hav-

ing a forward and return movement from and to its starting position, a spring to automatically return the driver and serving to limit its forward movement, means to adjust said spring to vary the throw of the driver, and an index set by the adjustment of said spring to automatically indicate the length of throw of the driver for any adjustment of the spring.

17. The combination with a rotary platen, and a driver to rotate the platen through a predetermined distance, said driver having a forward and return movement, of a stop to limit the return movement of the driver, a coil spring connected at one end to the driver for returning the latter, a support to which the opposite end of the spring is anchored, the forward movement of the driver being limited by said spring, said support adjustable to vary the throw of the driver, and an index comprising a scale and pointer relatively adjusted by the adjustment of said support to indicate the length of throw of the driver.

18. The combination with a rotary platen and platen axle, of means to rotate the platen through a predetermined fixed distance, said means comprising a driving element loosely mounted on the platen axle, means to connect said driving element to the platen, a stationary casing inclosing said element, a spring connected at one end to said driving element, said casing comprising a cover plate or cap to which the other end of the spring is connected, said spring limiting the forward rotation of the driving element and operable automatically to return said element, said cap rotatively adjustable to adjust said spring, and thereby vary the extent of rotation of said element, an index comprising a scale and pointer carried by said casing and cap, said scale having a series of numbers so spaced and arranged that the number opposite the pointer will always indicate the number of line-spaces through which the platen may be rotated by the driving element when said cap is in any position of adjustment.

19. The combination with a platen, of means to rotate the platen, said means comprising a lever having a handle and a driver, said lever and driver both having an axis of rotation coincident with the platen axis, means forming a driving connection between said handle and driver, whereby when the handle is moved in one direction, said driver is rotated in the reverse direction at a higher angular speed, and means to cause said driver, when rotated in one direction, to drive the platen in the reverse direction.

20. The combination with a rotary platen and platen axle, of driving means comprising a handle and a driver both loosely mounted for rotation on the platen axle, a flexible band forming a driving connection

between said driver and the handle, directing means for said band, whereby, when the handle is rotated about the platen axis in one direction, said driver is rotated in the reverse direction, and means for causing 5 said driver to rotate the platen.

21. The combination with a platen and a driver to rotate the platen, said driver having a forward and return movement from its normal position of rest, of an interponent between the driver and platen, the interponent being disconnected from the platen while the driver is in its normal position of rest to permit the platen to be rotated independently of the driver, said 10 driver having a lost motion connection with the interponent, the lost motion being taken up during the initial forward movement of the driver, means operated during said initial movement to connect the interponent with the platen to rotate the latter during the continued forward movement of the driver, the interponent being released from the platen during the initial portion of the 15 return movement of the driver, thereby permitting the platen to remain at rest during the return of the driver to its starting position, a spring to automatically return the driver to starting position, said spring also forming a means to limit the forward throw of the driver, and thereby determine the 20 distance through which the platen may be rotated by an operation of the driver, means forming an anchor for said spring, said anchor adjustable to vary the length of 25 throw of the driver, and means adjustable with said anchor to indicate the number of line-space distances through which the platen may be rotated by an operation of 30 the driver.

22. The combination with a platen and a rotary driving means for rotating the platen, of a coil spring connected at one end to the driving means, a stationary device 45 to which the other end of the spring is anchored, said spring permitting a limited rotation of the driving means in one direction and serving as a stop to limit said rotation, a stop to limit the rotation of said driving 50 means in the reverse direction, said device to which the spring is connected being adjustable to limit the position of the driving means determined by said spring and thereby vary the extent of rotation of the driving 55 means, and indicating means adjusted by the adjustment of said device to indicate the distance through which the platen may be rotated by an operation of the driving means.

23. The combination with a platen and platen axle, of a driving lever and an interponent through which the driving lever may drive the platen, said interponent and lever both loosely mounted for rotation on the 60 platen axle, mechanism forming a driving

connection between said lever and interponent, said mechanism comprising a flexible band and means to connect said band with the interponent, a guide pulley over which said band runs and whereby the band is directed to rotate the interponent in one direction when the lever is rotated in the opposite direction, and means to connect the platen with the interponent to be driven thereby in one direction and permitting the 70 interponent to rotate independently of the platen in the opposite direction.

24. The combination with a platen and platen axle, of a driving lever and an interponent through which the driving lever may drive the platen, said interponent and lever both loosely mounted for rotation on the platen axle, a flexible band, means forming with said band a driving connection between said lever and interponent, a guide pulley over which said band runs and whereby the band is directed to rotate the interponent in one direction when the lever is rotated in the opposite direction, means to connect the platen with the interponent to be driven thereby in one direction and permitting the interponent to rotate independently of the platen in the opposite direction, a stationary casing inclosing said interponent, a cover plate or cap for said casing and rotatably adjustable on the casing, and means forming a connection between said cap and said interponent to limit the rotation of the latter and thereby determine the distance through which the platen may be rotated at each operation of the driving lever, the adjustment of said cap serving to vary the extent of said rotation.

25. The combination with a platen and platen axle, of a driving lever and an interponent through which the driving lever may drive the platen, said interponent and lever both loosely mounted for rotation on the platen axle, a flexible band, means forming with said band a driving connection between said lever and interponent, a guide pulley over which said band runs and whereby the band is directed to rotate the interponent in one direction when the lever is rotated in the opposite direction, means to connect the platen with the interponent to be driven thereby in one direction and permitting the interponent to rotate independently of the platen in the opposite direction, a stationary casing inclosing said interponent, a cover plate or cap for said casing and rotatably adjustable on the casing, means forming a connection between said cap and said interponent to limit the rotation of the latter and thereby determine the distance through which the platen may be rotated at each operation of the driving lever, the adjustment of said cap serving to vary the extent of said rotation, 100 and thereby determine the distance through which the platen may be rotated at each operation of the driving lever, the adjustment of said cap serving to vary the extent of said rotation, 105 and thereby determine the distance through which the platen may be rotated at each operation of the driving lever, the adjustment of said cap serving to vary the extent of said rotation, 110 and thereby determine the distance through which the platen may be rotated at each operation of the driving lever, the adjustment of said cap serving to vary the extent of said rotation, 115 and thereby determine the distance through which the platen may be rotated at each operation of the driving lever, the adjustment of said cap serving to vary the extent of said rotation, 120 and thereby determine the distance through which the platen may be rotated at each operation of the driving lever, the adjustment of said cap serving to vary the extent of said rotation, 125 and thereby determine the distance through which the platen may be rotated at each operation of the driving lever, the adjustment of said cap serving to vary the extent of said rotation, 130

8
said cap and casing, the numbers being spaced and positioned relatively to the pointer to indicate for any adjustment of the cap, the number of line-space distances through which the platen may be rotated by each operation of the driver.

26. The combination with a platen, of a handle having a concentric axis of rotation with said platen, a ribbon connected at one end to said handle and at the other end to rotate said platen, and adjustable means connected to the latter end of said platen for variably limiting the driving movement of said handle and the rotary movement of said platen.

27. The combination with a rotary platen, of a platen frame, a handle mounted thereon, a band or flexible connection attached at one end to said handle, a driver revoluble about the platen axis and normally disconnected from said platen, the other end of said flexible connection being attached to said driver, a pulley on said platen frame over which said flexible connection runs between said handle and said driver, and means for releasably connecting said driver to said platen.

28. The combination with a rotary platen, of a platen frame, a handle mounted thereon, a band or flexible connection attached at one end to said handle, a driver revoluble about the platen axis and normally disconnected from said platen, the other end of said flexible connection being attached to said driver, a pulley on said platen frame over which said flexible connection runs between said handle and said driver, means for releasably connecting said driver to said platen, and a spring for returning said driver.

29. The combination with a rotary platen, of a platen frame, a handle mounted thereon, a band or flexible connection attached at one end to said handle, a driver revoluble about the platen axis and normally disconnected from said platen, the other end of said flexible connection being attached to said driver, a pulley on said platen frame over which said flexible connection runs between said handle and said driver, means for releasably connecting said driver to said platen, and a spring for returning said driver.

nected from said platen, the other end of said flexible connection being attached to said driver, a pulley on said platen frame over which said flexible connection runs between said handle and said driver, means 50 for releasably connecting said driver to said platen, and a spring for returning said driver, said flexible connection being wound around said driver more than once, to enable a single stroke of said handle to impart 55 more than an entire revolution to said platen.

30. The combination with a rotary platen, of a platen frame, a handle mounted thereon, a band or flexible connection attached at one end to said handle, a driver revoluble 60 about the platen axis and normally disconnected from said platen, the other end of said flexible connection being attached to said driver, a pulley on said platen frame over which said flexible connection runs between said handle and said driver, means 65 for releasably connecting said driver to said platen, a spring for returning said driver, and relatively adjustable stops for limiting the stroke of said driver.

31. The combination with a rotary platen, of a platen frame, a handle mounted thereon, a band or flexible connection attached at one end to said handle, a driver revoluble about the platen axis and normally disconnected from said platen, the other end of said flexible connection being attached to said driver, a pulley on said platen frame over which said flexible connection runs between said handle and said driver, means 75 for releasably connecting said driver to said platen, and coupling means operating to couple the driver to the platen upon one stroke of the handle, and to release the driver from the platen at the other stroke 80 of said handle.
